TREATMENT OF CRUDE TAR ACIDS
FRACTIONS

Vittorio Molinari, North Plainfield, N. J., assignor to Bakelite Corporation, a corporation of New Jersey

No Drawing. Application September 11, 1943,
Serial No. 591,992

6 Claims. (CL 260—627)

This invention relates to the preparation and isolation from crude tar acids of phenols suitable for reaction with formaldehyde to yield resins; these phenols comprise phenol (monohydroxy benzene) and the homologous methyl phenols which include cresols, xylenols, trimethyl phenols and tetramethyl phenols. At present it is the common practice to recover these phenols from crude tar acids produced in the high temperature carbonization of bituminous coals; and the phenols are obtained by washing the tar acids with aqueous caustic soda, separating by decanting from the oily layer the water layer carrying the phenolates in solution, concentrating the water layer to eliminate oily and pyridine impurities, and liberating the phenol mixtures by means of carbon dioxide or sulfuric acid. The mixtures of phenols are usually fractionated under vacuum into phenol, cresol and xylenol cuts, for each cut has a definite reactivity with formaldehyde.

Besides the crude tar acids obtained in high temperature coal distillation, there are large potential but unused sources of phenols for resin production. Among these sources are the crude tar acids produced in the carbonization of lignite and hard woods such as maple, oak, redwood and Douglas fir; other sources are the tar acids resulting from low temperature distillation and the hydrogenation of coal. Common to the tar acids from these sources is the presence therein of the alkyl ethers of dihydroxy benzenes or alkoxy-phenols, such as guaiacol and methyl guaiacol; the ethers or alkoxy-phenols in general are present in amount to constitute from 5 to 15 per cent and to impart an increase in the specific gravity to about 1.05 to 1.07 to mixtures of phenols separated from the crude tar acids. The ethers, however, are well-known inhibitors of the resin-forming reaction of phenol and the methyl phenols with formaldehyde; and if present in resins incorporated with drying oils to form varnishes, they act as strong retardants on the drying of the varnish coatings to extend the drying period many times the normal period. Accordingly their elimination is necessary before the phenol mixtures can be used for resin production. In a co-pending application Serial No. 324,322 filed March 16, 1940, there is disclosed a method for the elimination of such ethers, and the present application is a continuation-in-part thereof.

The invention claimed herein provides for the dealkylation of the ethers present in the crude tar acids without the isolation of objectionable phenols. At the same time it secures the removal

from the phenols of other compounds that constitute impurities, such as neutral oil, sulfur compounds including mercaptans, nitrogen bases (pyridine), thiophenols, etc.

It has been found that the foregoing objects can be accomplished by a process including the following steps:

(1) Treating the crude tar acids with aqueous caustic soda and decanting the solution of phenolates from the supernatant oily layer in the usual manner; this step can be the same as that for extracting crude tar acids from middle and heavy oils of coal tars from high temperature coal carbonization;

(2) Heating the aqueous phenolate solution to concentrate and raise the mass to a temperature that causes substantial dehydration and fusion of the mass; and

(3) Blowing the molten mass with a predetermined quantity of air carrying a definite proportion of water vapor.

The residue remaining after blowing is dissolved in water, acidified and rectified to yield a mixture of free phenols. Phenol mixtures, so isolated from crude tar acids resulting from the distillation of hard woods, etc. and containing methoxy phenols, are found to have substantially the specific gravities and rates of reactivity with formaldehyde that characterize free phenol mixtures of the same boiling range obtained from crude tar acids resulting from high temperature coal distillation.

The phenolates, prepared according to step (1), are concentrated in step (2) by boiling off water and continuing the heating to the fusion temperature of the crude phenolate. It has been found essential to the effectiveness of the succeeding step of blowing that the mass be at a fusion or melting temperature, generally ranging from about 280° to 360° C., though in some cases it may be as low as 160 or 210° C.

The step (3) of blowing with air carrying a definite proportion of water is accomplished by bubbling the air through water at a predetermined temperature whereby the air becomes saturated at that temperature; bubbling through water at about 90° C., as a rule, has been found to supply the proportion of water required and to maintain the mass in the condition of concentration and fusion without the mass becoming unduly dry and without increasing the fusion temperature. At the high fusion temperatures employed, an excess over the quantity of air required causes decomposition of the useful phenols, and it is therefore necessary to stop the air flow

before such decomposition begins; this is determined by preliminary experiment and analysis.

During the blowing step (3) at the fusion temperature by the air stream carrying water vapor, the alkoxy groups are split off by hydrolysis as is shown by the alcohols collected in the condensate; in fact the action is found to be quantitative and rapid. In addition the offensive odor due to mercaptans and other sulfur compounds disappears; and remaining objectionable impurities are removed, or those that remain have such high boiling points in comparison with the useful phenols that the latter are readily separated by distillation following acidification and rectification.

In a German Patent No. 584,857 to Meyer it has been proposed to purify phenols obtained in the distillation of a form of lignite, according to the example, by passing a cold air current for several hours through a caustic soda extraction of tar fraction, thereafter steam is introduced while the solution is heated in an oil bath to 220° C. to drive off impurities, the solid residue is dissolved in water and the phenolate solution is acidified to yield a cresol fraction. The impurities mentioned in the patent are dihydroxy benzenes and mercaptans which are attacked by oxidation at ordinary temperatures, as the patent acknowledges, and some basic oils having the odor of quinolines and probably hydrated in the course of the steam distillation.

Such a process, however, does not cause dealkylation of alkoxy phenols or ethers. Oxidation alone is not operative for the purpose, for at room temperature no such reaction takes place; and, if the mass is elevated to fusion or melting temperatures, the oxidation becomes energetic with decomposition and cracking into high-boiling and tarry products constituting a loss that may reach 40 to 50 per cent of the original mass. Nor is steam distillation alone at fusing or melting temperature of any benefit, as far as the splitting-off of the alkyl groups of the ethers is concerned; while the action is apparently one of hydrolysis as indicated by the alcohols found in the distillate, steam alone is not enough and oxygen is also required. Essential to the present invention, therefore, is the conjoint passage of steam and air through the mass at fusion or melting temperature.

Example.—Four thousand (4000) parts of tar acids with a boiling range between 200° C. and 250° C. separated from tar obtained by carbonizing redwood showed a methoxy content of about 6 per cent; when rectified for analysis, a fraction boiling between 200° C. and 205° C. had a methoxy content of 7 to 7.5 per cent and a specific gravity at 15.6° C. of 1.05 to 1.076, and a fraction boiling between 220° C. and 225° C. had a methoxy content of 7.5 to 8 per cent and a specific gravity at 15.6° C. of 1.06 to 1.07. The crude tar acids were dissolved in an aqueous solution containing 1200 parts of caustic soda, and the water solution of the phenolates was concentrated by evaporation while being agitated. When the molten mass reached a temperature of 280° C., a current of air that had been previously bubbled through water heated to 90° C. was blown through the molten mass for about an hour until 15 cubic feet of air per gallon of tar acids used passed therethrough, and the temperature increased to 300° C. to 320° C. The residue remaining in the retort was dissolved in water, acidified, and then fractionally distilled. The fraction collected at 200° C. to 205° C. had a specific gravity of 1.033 to 1.035, and this is very close to that of a cresol cut obtained from

tar acids prepared from tar of high temperature coal carbonizations; moreover, the fraction had no guaiacol odor and contained no methoxy groups and therefore could be tested for metacresol by the Raschig methods, which was impossible with the original tar acids because of the guaiacol present. The fraction collected at 220° C. to 225° C., showed a much improved reactivity with formaldehyde, and the odors characteristic of the tar acids of wood carbonization were absent.

The example demonstrates the effectiveness of the conjoint passage of air and steam for the dealkylation of alkyl-phenol ethers with the elimination of the methoxy groups; by alkyl-phenol ethers are intended mixed ethers containing both an alkyl and an aryl group and in which the aryl group has a hydroxyl substituted for a hydrogen on the ring. The process is not restricted to tar acids of the example or to the splitting off of methoxy groups; it is generally applicable to other sources of tar acids, such as those obtained from lignite and low temperature coal distillation, that contain objectionable amounts of the ethers, and applicable to the dealkylation of other alkyl-phenol ethers. The character and amounts of phenols and other ingredients present in the tar acid fraction treated in general controls the temperature to which the mass is raised for concentration of the water content and melting; as indicated, melting may be attained at temperatures as low as 160° C. to 180° C. for fractions collected within a correspondingly low boiling range and substantially dehydrated to the extent of about 60 per cent or more. The amount of air saturated with water vapor at about 90° C. required for the dealkylation varies with the alkoxy-phenol content, and it can be determined by a preliminary analysis on a sample; but in general it ranges from about 10 to 15 cubic feet per gallon of tar acid fraction treated by the process.

The dealkylation of the ethers probably results in the formation of caustic soda compounds of dihydroxy benzenes, and particularly of catechol under the described conditions of concentration and melting. These are likewise undesirable; but apparently they become oxidized, since they do not appear among the phenols freed by dissolving the residue in water, then acidifying the water solution and rectifying.

What is claimed is:

1. Process of treating a crude tar acid fraction containing an alkyl-phenol ether which comprises extracting the acid content by aqueous caustic soda and separating the aqueous layer, heating the aqueous layer to substantially dehydrate and melt the mass, and passing through the molten mass a current of air containing water vapor in amount to cause dealkylation.

2. Process of treating a crude tar acid fraction obtained in the carbonization of wood containing a methoxy-phenol which comprises extracting the acid content by aqueous caustic soda and separating the aqueous layer, heating the aqueous layer to substantially dehydrate and melt the mass, and passing through the molten mass about fifteen cubic feet of air per gallon of the tar acid fraction previously bubbled through water at 90° C.

3. Process of dealkylating an alkyl-phenol ether which comprises reacting with sodium hydroxide in aqueous solution, heating the solution to substantially dehydrate and melt the resulting mass, and passing through the molten mass a

current of air containing water vapor in amount to cause dealkylation.

4. Process of dealkylating an alkyl-phenol ether which comprises hydrolyzing a concentrated and molten mass of a sodium phenolate of the ether by passing through the mass a current of air containing water vapor.

5. Process of dealkylating an alkyl-phenol ether to a corresponding phenol which comprises hydrolyzing a molten mass of a sodium phenolate of the ether by passing through the mass a cur-

rent of air containing water vapor, and acidifying the mass to free the phenols.

6. Process of dealkylating an alkyl-phenol ether to a corresponding phenol which comprises reacting the ether with sodium hydroxide in aqueous solution, heating the solution to substantially dehydrate and melt the resulting mass, passing through the molten mass a current of air containing water vapor in amount to cause dealkylation, and acidifying the mass to free the phenols.
